UNITED STATES PATENT OFFICE.

EMIL G. SAUER, OF BROOKLYN, NEW YORK, ASSIGNOR TO THE LOWELL MANUFACTURING COMPANY, OF MASSACHUSETTS.

DESIGN FOR CARPET.

SPECIFICATION forming part of Design No. 24,672, dated September 10, 1895.

Application filed August 8, 1895. Serial No. 558,166. Term of patent 3½ years.

To all whom it may concern:

Be it known that I, EMIL G. SAUER, a citizen of the United States, and a resident of Brooklyn, in the county of Kings, State of New York, have invented a new and original Design for Carpet, of which the following is a specification.

This invention comprises two parts—namely, the design A for a carpet and the design B for a border; and I do hereby declare that the drawing accompanying this specification conveys to any one a clear understanding of the same, and is sufficient to enable such person to use my invention.

15 The design A is characterized by large figures having irregular curving outlines and by conventional leaf forms constituting its leading feature.

The design B is characterized by a panel of

large figures having irregular curving outlines and by conventional leaf forms somewhat similar to the design A and constituting its leading feature.

What I claim, and desire to secure by Letters Patent, is—

1. In a design for a carpet, the body A, substantially as shown.
2. In a design for a carpet, the border B, substantially as shown.
3. In a design for a carpet, the body A and 30 the border B, substantially as shown.

In testimony whereof I have signed my name to this specification in the presence of two subscribing witnesses.

EMIL G. SAUER.
